(57) **CLAIM**

We claim the ornamental design for the hand held computer with keyboard, as shown and described.

DESCRIPTION

FIG. 1 is a front elevation view of a hand held computer with keyboard.

FIG. 2 is a left side elevation view.

FIG. 3 is a right side elevation view; and,

FIG. 4 is a top plan view.

The broken line disclosure, for example of the hand held computer environment, is for illustrative purposes only and forms no part of the claimed design.
